CLAIM

The ornamental design for a plant-growing tray, as shown and described.

DESCRIPTION

FIG. 1 is a perspective view of a plant-growing tray from above;

FIG. 2 is a perspective view of a plant-growing tray from below;

FIG. 3 is a top view of a plant-growing tray;

FIG. 4 is a bottom view of a plant-growing tray;

FIG. 5 is a view of the long side of a plant-growing tray;

FIG. 6 is a view of the short side of a plant-growing tray;

FIG. 7 is a detail view of a portion of the perspective view of a plant-growing tray from above from FIG. 1;

FIG. 8 is a detail view of a portion of the perspective view of a plant-growing tray from below from FIG. 2;

FIG. 9 is a detail view of a portion of the top view of a plant-growing tray from FIG. 3; and,

FIG. 10 is a detail view of a portion of the bottom view of a plant-growing tray from FIG. 4.
